UNITED STATES PATENT OFFICE.

WILLIAM GEORGE HARRIS AND HARRY HARRIS, OF LONDON, ENGLAND.

FASTENING DEVICE.

1,092,647.

Specification of Letters Patent. Patented Apr. 7, 1914.

Application filed June 2, 1913. Serial No. 771,288.

To all whom it may concern:

Be it known that we, WILLIAM GEORGE HARRIS and HARRY HARRIS, subjects of the King of England, residing at 7 Charterhouse street, London, E. C., England, have invented certain new and useful Improvements in or Relating to Fastening Devices, of which the following is a specification.

This invention relates to clips, buckles, or similar devices for use in fastening or tightening a strap, belt, or like attaching means, and relates more particularly to that type of device wherein two members with transverse slots are movable relatively to each other for the purpose of gripping a strap or the like when passed between the slots.

To this end the invention particularly consists of a casing formed of an upper and a lower plate with transverse slots registering with each other, the slot in the upper plate being wider than the slot in the lower plate, and a flat locking plate freely slideable between the upper and lower plates and having a transverse slot which when in its rear position is in register with the slots in both plates but when in its forward locking position is only in register with the slot in the upper plate, the arrangement being such that upon the insertion of a strap, belt or the like the movable member is displaced by the contact with the strap so that its slot comes into register with the slot in the lower plate. Through these slots the strap or belt or the like is then inserted and on subsequently exerting a pull on the strap or belt, the sliding plate is automatically drawn forward so that the strap or belt is firmly gripped between the edges of the slots in the sliding and lower plates and the more the strap or belt is pulled in this particular direction the tighter is the grip exerted thereon, as will be more fully understood from a description of the accompanying drawings in which—

Figure 1 illustrates by way of example the use of the improved clip for a watch strap bracelet. Fig. 2 is an enlarged sectional view on the line A—B of Fig. 1, of one of the clips or fastening devices showing the parts in normal position, *i. e.* prior to the insertion of the strap, of which the bracelet consists, in the direction of the arrow 2. Fig. 3 is a view similar to Fig. 2 showing the parts in the position which they assume upon the insertion of the end of the strap in the direction of the arrow 3. Fig. 4 is

a view similar to Figs. 2 and 3, showing the parts in their gripping position which they assume on the strap being pulled in the direction of the arrow 4, and Fig. 5 is a top plan view of one of the clips with the upper plate partly broken away, and showing the movable plate or slide also partly broken so as to clearly show the position of the lower plate within a casing which is indicated in section.

In the example illustrated in the drawing, the fastener *a* consists of a casing *b* which by means of a hinge *c* or in some other convenient manner is attached to suitable lugs of a watch, if it is desired to use the fastener for the attachment of a watch bracelet as shown. The top or cover plate *d* of this casing is provided with a slot *e* confined at its forward edge by a narrow preferably raised ledge or cross piece *f*, this slot being of such width that in any position of the sliding plate *k* it registers with the slot therein. At its front face the casing *b* is provided with a slot *g* serving for the insertion of the edge or end of the strap or belt or like means *h* to be secured by the fastener. Arranged within the casing *b* and formed integral therewith is a plate *i* which is provided with a transverse slot *j*. Said plate *i* forms a recess with the bottom wall of the casing, and said recess is adapted to receive the free end of the inserted strap, as shown in Figs. 3 and 4. Located immediately above the plate *i* and guided thereon is a movable plate or slide *k* provided with a transverse slot *l*. The slide *k* has its longitudinal edges guided by the adjacent longitudinal walls of the casing, but in order to enable it to be longitudinally moved within the casing it is of course slightly shorter than the casing as shown, so that a play space is formed substantially equal to the width of the slot *l*. This slide *k* moreover, is guided and confined by the upper plate *d*, while its thickness is so chosen that, as indicated particularly in Fig. 2, its forward top edge lies slightly above the bottom edge of the slot *g* through which the strap *h* is inserted.

Normally that is to say, before the insertion of the strap, the parts may be in any desired position, for instance in that shown in Fig. 2, in which the slot *l* in the slide *k* lies forward of the slot *j* in the stationary member *i*. Now by inserting the edge of the strap *h* through the slot *g* in the direc-

tion of the arrow 2 in Fig. 2 the slide *k* is displaced, that is to say, is forced back, by the edge of the strap thereby assuming the position shown in Fig. 3, in which the 5 slots *l* and *j* register with one another. In this position the slide *k* is held by the body of the strap and the edge of the latter is now inserted through the registering slots *l*, *j* so as to pass beneath the transverse edge 10 of the lower plate *i* into the compartment formed between it and the bottom of the casing *d*. By then exerting a pull on the strap *h* in the direction of the arrow 4, as indicated in Fig. 4, the slide *k* is pulled forward by the strap, whereby the slot *l* is again relatively displaced with regard to the slot *j* and by this action the portion of the strap lying between the slots is caused to be gripped between the forward top edge 15 of the slot in the plate *i* and the rear bottom edge of the slot in the slide *k*, as can be clearly seen from Fig. 4. In this manner the end or body of the strap is firmly gripped within the clip and it will be understood that the stronger the pull which is exerted on the strap in the direction of the 20 arrow 4 the firmer is the grip produced thereby between the operative gripping edges of the fastener members. In order to release this grip it suffices to move the strap *h* in a direction opposite to that of the arrow 4, whereby the slide *k* is moved rearwardly, and the edge of the strap can be 25 readily withdrawn and re-inserted if desired.

Although the invention has been described and illustrated in the shape of a clip more

particularly applicable for watch bracelets it is obvious that it may be applied for other purposes.

40

What we claim and desire to secure by Letters Patent is:—

1. A buckle comprising a member provided with a recess, a slideway, and opposed slots; a cross piece providing an opening to receive a strap; a plate slidable within said slideway and within said strap opening, and provided with a slot; said slots adapted to register and receive a strap passing through said opening and into the recess; and said plate adapted to be moved to offset the slots and constrict said opening to secure the strap.

2. A buckle comprising a casing, a plate fixed therein and providing therewith a recess and a slideway, a slot in the casing; a cross piece providing an opening to receive a strap; said fixed plate providing a slot adjacent one end of said recess; a plate provided with a slot slidable in said slideway and within the opening provided by said cross piece; said slots adapted to register and receive a strap passing through said opening and into the recess; and said slidable plate adapted to be moved to offset the slots and constrict said opening to secure the strap.

In testimony whereof we have affixed our signatures in presence of two witnesses.

WILLIAM GEORGE HARRIS.
HARRY HARRIS.
